UNITED STATES PATENT OFFICE

ALBRECHT VON FRANKENBERG, OF GELSENKIRCHEN, GERMANY, ASSIGNOR, BY MESNE ASSIGNMENTS, TO DURAVER (INC.), OF DOVER, DELAWARE, A CORPORATION OF DELAWARE

CENTRIFUGAL CASTING MACHINE

Application filed September 11, 1930. Serial No. 481,156.

The present invention relates to casting machines and embodies, more specifically, an improved centrifugal casting machine which operates upon a vertical axis. More specifically, the invention relates to an improved machine for casting articles centrifugally, the machine being so formed as to adapt the mold and core to be readily separated in order that the removal of the casting therefrom may be facilitated.

The art of centrifugal casting has heretofore been extended to devices for casting pipes and the like upon a horizontal axis. In these existing forms of casting machines cores have been used to form bell ends and the like upon pipe sections, the cylindrical portion of the pipe being formed without a core by the rapid rotation of the mold as distinguished from the previous casting methods. The present invention provides a device for casting in a vertical axis, the device including a core for forming the inner surface of the casting, the core and mold being relatively movable axially to effect the removal of the casting therefrom.

In order to expedite the successive casting operations, the mold, in accordance with the present invention, is adapted to be cooled effectively by means of a cooling fluid which may be so controlled as to preserve a desired mold temperature uniformly during successive casting operations. Improved means is further provided for mounting the rotatable mold and for imparting rotation thereto, the construction and coaction of the core with the mold being such that it may be readily removed to provide for the removal of the casting from the machine.

An object of the invention, accordingly, is to provide an improved molding machine by means of which the mold temperature may be effectively controlled.

A further object of the invention is to provide a machine of the above character, wherein in cooling thereof is effected in accordance with desired conditions of operation.

A further object of the invention is to provide a mold of the above character, wherein successive pourings and castings may be readily effected.

A further object of the invention is to provide a mold of the above character, the core whereof is readily removable to effect the removal of the casting.

A further object of the invention is to provide a mold of the above character, wherein rotation is imparted thereto through a simple and effective mechanism, at the same time preserving the accessibility and interchangeability of the core.

A further object of the invention is to provide a mold of the above character, wherein the same is effectively mounted for rotation, means being provided to removably secure the core thereto.

A further object of the invention is to provide a method for manufacturing a brake drum, such method comprising casting the same centrifugally in an improved fashion.

A further object of the invention is to provide an improved unitary cast brake drum.

Further objects, not specifically enumerated above, will be apparent as the invention is described in greater detail in connection with the accompany drawings, wherein:

Figure 1 is a view in vertical section, taken through the axis of a mold constructed in accordance with the present invention and showing the cooling mechanism, rotating mechanism and core supporting means, in addition to cooperating structure therefor.

Figure 2 is a segmental plan view showing the mold of Figure 1.

Figure 3 is a view in section, similar to Figure 1, but showing a modified mold structure and cooling means therefor.

Figure 4 is a view in section, taken on line 4-4 of Figure 1, and looking in the direction of the arrows.

Figure 5 is a view in section, taken on line 5-5 of Figure 4, and looking in the direction of the arrows.

Figure 6 is a segmental view in section, showing a brake drum constructed in accordance with the present invention.

With reference to the construction shown in Figures 1, 2, 4, and 5, a base or supporting element is shown at 1 as having flanges 2 by means of which the structure is secured to a floor or other supporting surface. The base

100

has been shown as cylindrical although its specific form constitutes no part of the present invention since it is obvious that such may be varied at will. Upon opposite sides of the base, openings 3 are formed, these openings facilitating the removal of the casting from the machine. About the upper periphery of the base, spaced lands 4 are formed, these lands receiving standards 5 upon which rollers 6 are journaled. In this fashion the weight of the mold structure is rotatably mounted upon the base and, in addition to the lands 4, lands 7 are formed on the base to mount horizontally adjustable rollers 8 for imparting lateral stability to the mold and preventing vibration thereof during rotation.

A bracket 9 is secured to the side of the base 1 at a suitable height to mount a driving motor 10 which drives a shaft 11 to which a bevel gear 12 is secured. The shaft 11 is journaled at 13 in a suitable fitting carried by the base 1 and the mold structure is thus conveniently rotated by the foregoing mechanism which cooperates with driving mechanism formed on the rotatable mold.

A rotatable mold is shown at 14 having an outer wall 15 and a molding surface 16. The molding surface terminates in an upwardly extending funnel 17 through which a molten metal is poured in casting. The funnel preferably has a bushing 18 secured thereto and receives a stationary funnel portion 19 which is carried upon a horizontal frame 20. Vertical supporting members 21 mount the frame upon the base 1 as will be clearly apparent from Figure 1.

A mold cover 22 is secured to the outer wall of the mold by a series of bolts 23 and is formed with an aperture 24 adjacent which an extension 25 is provided forming a sealing groove 26. Spaced about the periphery of the outer wall 15 are a plurality of outlet pipes 27 which extend into an annular enclosed trough 28 formed with an annular groove 29 for receiving the outlet pipes. In this fashion, cooling fluid may be withdrawn from the chamber formed by the outer wall 15 and the molding surface 16 of the mold, the fluid being introduced through pipes 30 which are carried by the frame members 21 and have downwardly extending portions 31 which are received within the aperture 25.

In the form shown herein the outer wall 15 and molding surface 16 are formed as separate units and mounted upon an annular base 32 having a cylindrical portion 33 and an annular flange 34 upon which a rack 35 is secured. This rack is adapted to engage the gear 12 and thus transmits rotary motion to the mold.

Extending through the cylindrical portion 33 of the base are a plurality of removable keys 36 which are adapted to engage the outer periphery of a core 37. It will be apparent

that the core may be removed from the mold by removing the keys 36 and dropping the same in a manner which will be described in greater detail hereinafter.

The shape of the core and mold surface has been shown as of such character as to form a brake drum having the characteristics shown in Figure 6. This brake drum is formed with a dust flange 38, a cylindrical drum portion 39 and a disc or spider 40. When the mold is rotating at a sufficient speed, metal is introduced thereinto through the funnel 19 and the enormous force exerted upon the particles of metal by the centrifugal action thereof serves to produce a brake drum, the metal of which is extremely dense and the characteristics of which are those enumerated hereinbefore. After the metal has been cast, the core and cast drum are removed by elevating a suitable table, indicated in dot and dash lines at 41, and removing the keys 36. The table is then dropped with the mold and casting and the latter removed through one of the openings 3. If desired, a conveyor 42 may be provided, as indicated in dot and dash lines in Figures 4 and 5, to facilitate the removal of the core and casting and a fresh core may be inserted through the other opening and secured in position in a manner which will be readily understood. It is desirable, of course, to provide notches in the table 4 and to receive the ends of the keys 36 and thus permit the table to be elevated into direct contact with the core 37.

The cooling of the mold is effected in the manner outlined above. By regulating the flow of the cooling fluid through the pipes 30, the temperature of the mold may be preserved at any desired value, the discharge of the fluid from the mold being effected as described above. It will be understood that the fluid may be carried away from the trough 28 in any desired fashion, this trough being mounted upon the stationary portion of the mold by means of suitable angle irons 43.

From the foregoing, it will be seen that the casting operation whereby centrifugal castings are formed is greatly simplified by the construction described herein. Repeated castings may be made and the mold may function continuously with but a comparatively slight amount of manual supervision. The specific form of the mold elements may be varied, if desired, a modified form being illustrated in Figure 3, wherein the outer wall 50 of the mold is formed with cylindrical flanges 51 and 52. The wall is mounted upon the stationary portion 53 of the frame and is adapted to cooperate with a molding surface 54 which is mounted upon a rotatable base 55, the rotation thereof being effected in a manner similar to that described in connection with the device shown in Figure 1. The molding surface is formed with a cylindrical

neck 56 which is formed with a reentrant cylindrical flange 57, adapted to be received within the flange 51 and seal the same. A funnel 58 is mounted upon the stationary 5 outer wall 50 and extends within the neck 56 to serve as a sealing member for the top of the mold.

The rotatable molding surface is also formed with a reentrant cylindrical flange 10 59 which is adapted to cooperate with the flange 52 to seal the joint between the stationary and rotatable elements. A sealing member 60 is preferably inserted between the flanges to seal the joint effectively and the 15 rotatable elements are thus adapted to cooperate effectively with the stationary elements of the mold to provide an efficient molding device.

The cooling of the mold is effected by a 20 liquid 61 which is provided within the chamber formed between the outer wall and the molding surface 64. A coil 62 is provided within the chamber and communicates with inlet and outlet pipes 63, whereby the cooling 25 medium 61 may be cooled at any desired rate thus preserving the temperature of the medium at a predetermined desired value. It has been found desirable to select a cooling 30 medium having a high boiling point, the cooling thereof being effected at any desired rate by means of the coil 62 through which water is directed.

While the invention has been described with specific reference to the accompanying 35 drawings, it is not to be limited, save as defined in the appended claims.

I claim as my invention:

1. A casting machine comprising a base, a mold, means to mount the mold on the base 40 with a capacity for rotation about its vertical axis, a core, means on the mold to secure the core removably to the lower side thereof, means to lower the core with the casting away from the mold, teeth on the mold, and means 45 on the base to engage the teeth and rotate the mold.

2. A casting machine comprising a base, a mold, means to mount the mold on the base with capacity for rotation about its vertical 50 axis, a core, means on the mold to secure the core removably to the lower side thereof, means to lower the core with the casting away from the mold, a gear ring on the mold, a shaft journaled in the base, and a gear on the 55 shaft to engage the gear ring.

3. A casting machine comprising a base, a mold, means to mount the mold on the base with capacity for rotation about its vertical axis, a core, means on the mold to secure the 60 core removably to the lower side thereof, means to lower the core with the casting away from the mold, and means to rotate the mold, the base being formed with an aperture 65 through which access is provided to the core.

4. A casting machine comprising a base, a

mold, means to mount the mold on the base with capacity for rotation about its vertical axis, a core, means on the mold to secure the core removably to the lower side thereof 70 and means to lower the core with the casting away from the mold, a side of said base being so formed as to provide access to the core to facilitate removal thereof independently of the mold.

5. A casting machine comprising a base, 75 a plurality of lands on the base, rollers journaled upon horizontal axes upon certain of the lands, rollers journaled upon vertical axes upon other of the lands, a mold, and tracks on the mold to engage the respective lands. 80

6. A casting machine comprising a base, a plurality of lands on the base, rollers journaled upon horizontal axes upon certain of the lands, rollers journaled upon vertical axes upon other of the lands, a mold, and a horizontal flange on the mold, said flange being 85 formed with a horizontal and a cylindrical surface to engage the respective rollers.

7. A casting machine comprising a base, a mold mounted thereon rotatably, a core disposed within the mold and concentric therewith, a chamber formed on the mold, outlet pipes extending from the periphery of the chamber, an annular trough for receiving a cooling medium from the pipes, and means to 90 lower the core away from the mold. 95

8. A casting machine comprising a base, a mold mounted thereon rotatably, a core disposed within the mold and concentric therewith, a chamber formed on the mold, outlet 100 pipes extending from the periphery of the chamber, an annular trough for receiving a cooling medium from the pipes, means for supporting the trough upon the base, and means to lower the core away from the mold. 105

9. A casting machine comprising a base, a mold mounted thereon rotatably, a jacket for the mold forming a chamber about the mold for receiving a cooling fluid, said jacket having a horizontal portion formed with an aperture, a spout on the mold extending upwardly axially thereof, and means to introduce a cooling medium into the jacket through the aperture. 110

10. A casting machine comprising a base, a mold mounted thereon rotatably, a jacket for the mold forming a chamber about the mold for receiving a cooling fluid, a supporting ring mounting the jacket and mold, and means to rotate the ring. 115

11. A casting machine comprising a base, a mold mounted thereon rotatably, a jacket for the mold forming a chamber about the mold for receiving a cooling fluid, a supporting ring mounting the jacket and mold, a 120 horizontal flange on the ring, means associated with the ring for mounting a core, and means to rotate the flanges.

12. A casting machine comprising a base, a mold mounted thereon rotatably, a jacket for 125

the mold forming a chamber about the mold for receiving a cooling fluid, a supporting ring mounting the jacket and mold, a horizontal flange on the ring, keys mounted 5 radially on the ring for mounting a core, and an annular rack on the horizontal flange.

This specification signed this 27th day of May, A. D. 1930.
